(57) **CLAIM**

The ornamental design for a flashlight, as shown and described.

DESCRIPTION

FIG. 1 is a front view of the flashlight of my new design according to a first embodiment;

FIG. 2 is a rear view thereof according to the first embodiment;

FIG. 3 is a left view thereof according to the first embodiment;

FIG. 4 is a right view thereof according to the first embodiment;

FIG. 5 is a top view thereof according to the first embodiment;

FIG. 6 is a bottom view thereof according to the first embodiment;

FIG. 7 is a front perspective view thereof according to the first embodiment;

FIG. 8 is a rear perspective view thereof according to the first embodiment;

FIG. 9 is a bottom perspective view thereof according to the first embodiment;

FIG. 10 is a front perspective view thereof according to the first embodiment, illustrating a head portion being rotated with respect to a handle portion;

FIG. 11 is a bottom perspective view thereof according to the first embodiment, illustrating the head portion being rotated with respect to the handle portion;

FIG. 12 is a front perspective view thereof according to the first embodiment, illustrating a right angle between the head portion and the handle portion after the head portion is rotated;

(Continued)

FIG. 13 is a bottom perspective view thereof according to the first embodiment, illustrating the right angle between the head portion and the handle portion after the head portion is rotated;

FIG. 14 is a front view of the flashlight of my new design according to a second embodiment, wherein the second embodiment is an alternative mode of the first embodiment to illustrate a modification of a neck of the handle portion of the flashlight;

FIG. 15 is a rear view thereof according to the second embodiment, illustrating a modification of the flashlight without a clip in the second embodiment;

FIG. 16 is a left view thereof according to the second embodiment;

FIG. 17 is a right view thereof according to the second embodiment;

FIG. 18 is a top view thereof according to the second embodiment;

FIG. 19 is a bottom view thereof according to the second embodiment;

FIG. 20 is a front perspective view thereof according to the second embodiment;

FIG. 21 is a rear perspective view thereof according to the second embodiment;

FIG. 22 is a bottom perspective view thereof according to the second embodiment;

FIG. 23 is a front perspective view thereof according to the second embodiment, illustrating a head portion being rotated with respect to a handle portion;

FIG. 24 is a bottom perspective view thereof according to the second embodiment, illustrating the head portion being rotated with respect to the handle portion;

FIG. 25 is a front perspective view thereof according to the second embodiment, illustrating a right angle between the head portion and the handle portion after the head portion is rotated;

FIG. 26 is a bottom perspective view thereof according to the second embodiment, illustrating the right angle between the head portion and the handle portion after the head portion is rotated;

FIG. 27 is a front view of the flashlight of my new design according to a third embodiment, wherein the third embodiment is an alternative mode of the first embodiment to illustrate a modification of button-less of the flashlight in the third embodiment;

FIG. 28 is a rear view thereof according to the third embodiment;

FIG. 29 is a left view thereof according to the third embodiment;

FIG. 30 is a right view thereof according to the third embodiment;

FIG. 31 is a top view thereof according to the third embodiment;

FIG. 32 is a bottom view thereof according to the third embodiment;

FIG. 33 is a front perspective view thereof according to the third embodiment;

FIG. 34 is a rear perspective view thereof according to the third embodiment;

FIG. 35 is a bottom perspective view thereof according to the third embodiment;

FIG. 36 is a front perspective view thereof according to the third embodiment, illustrating a head portion being rotated with respect to a handle portion;

FIG. 37 is a bottom perspective view thereof according to the third embodiment, illustrating the head portion being rotated with respect to the handle portion;

FIG. 38 is a front perspective view thereof according to the third embodiment, illustrating a right angle between the head portion and the handle portion after the head portion is rotated; and,

FIG. 39 is a bottom perspective view thereof according to the third embodiment, illustrating the right angle between the head portion and the handle portion after the head portion is rotated.
